(57) **CLAIM**

We claim the ornamental design for a wave style kennel, as shown and described.

DESCRIPTION

FIG. 1 is a top-left perspective view of a wave style kennel showing our new design;

FIG. 2 is a front elevation view;

FIG. 3 is a rear elevation view;

FIG. 4 is a left-side elevation view;

FIG. 5 is a right-side elevation view;

FIG. 6 is a top plan view; and,

FIG. 7 is a bottom plan view.

In the drawings, the broken lines depict unclaimed subject matter only and form no part of the claimed design.
